METHOD OF REMODELING LASTS

John D. Owen, Stoughton, Mass.

Application November 30, 1939, Serial No. 306,819

1 Claim. (Cl. 12—146)

This invention relates to improvements in methods of remodeling lasts.

More particularly it relates to the remodeling of a last by substituting a new forepart.

Changes of styles in shoes entail heavy expense because lasts which are sound and mechanically good have to be discarded. It has long been recognized that large economy would result, if a practicable way were known for changing the forepart of a last.

Proposals to make lasts with detachable foreparts and a plurality of substitute foreparts have not won general acceptance, because mechanical fastenings become loose; and because style changes occur, unforeseen; and because of various other objections.

Proposals to remodel integral lasts have been by substituting a rough block for a severed forepart and then, with the block secured to the residue of old last, turning the block to the desired new shape of forepart. This procedure has proven unsatisfactory for various reasons, including the inability to mount in a lathe, because of the absence of old centers, and the extreme difficulty of shaping the new forepart precisely to desired contour without shaving or otherwise removing stock from the adjacent residue of the old.

The present invention starts with a last in which the body and toe are one integral piece, actually or in effect. This may carry such surface plates as may be wanted; and the body and heel may have whatever hinge, or block, or other arrangement may be preferred for extracting the last from the shoe. In the remodeled last which the invention provides, the connection of toe to body is integral, in the practical sense of being permanently rigid and secure, although the toe is in fact a separate piece of wood fastened to the body.

It is a characteristic of the present invention that the new forepart and the old body part fit together with perfect joinder of adjacent surfaces, without any wastage of material of the body, notwithstanding the difficulties above mentioned, arising from absence of turning centers and from diverse settings in the lathe of manufacture and the lathe of the remodeling.

Since the remodeling is effected without the old body having been made initially attachable and detachable, with respect to the forepart, it is an advantage of my invention that it can be applied to any of existing millions of ordinary wood lasts (assuming the old body to be adequate), with the effect of converting an old last of no value into a new one at not much more than the cost of mak-

ing the new fore portion. And this can be repeated an indefinite number of times. It is assumed in each case that all of the desired remodeling can be expressed in the fore portion— which is usually the fact. The place for severing toe from body can be selected as far back from the tip as may be necessary in order that the severed fore portion shall include all of the places where the contour of the last is to be changed, provided of course that it be forward of the hinge, if any, so that the saw does not find metal in its line of cut. Outside plates, if any, can be removed for the sawing, and replaced. The new part which is to replace the severed portion may be longer or shorter, wider or narrower, thicker or thinner, made with more spring, or more swing, or less of either, and may embody any variations in other respects as if the new fore part were an integral part of a new entire last. The special sawing of the forward end of the body, and sawing of the rear end of the forepart, make the smooth joinder of their respective contours.

This application is a continuation in part of my co-pending application Serial No. 113,816, filed December 2, 1936, and entitled Methods of and apparatus for remodeling lasts, wherein is disclosed and claimed apparatus suitable for performing the method as herein claimed. The apparatus herein disclosed embodies improvements over the apparatus of my said co-pending application Serial No. 113,816.

It is intended that the patent shall cover, by suitable expression in the appended claim, whatever features of patentable novelty of art or method exist in the invention disclosed.

In the accompanying drawings:

Figure 1 is a top plan of a device suitable for practicing my improved method of remodeling lasts, a complete last being shown mounted therein, in position for a straight saw cut, indicated by dotted lines, to partially sever its forepart from its rear part;

Figure 2 is a similar view showing the last moved to a position for a second straight saw cut, indicated by dotted lines, to complete the severing;

Figure 3 is an end elevation of the device as seen in Figure 2, looking at the forward end;

Figure 4 is a partial side elevation, in section on 4—4 of Figure 1;

Figure 5 is a top view, in section on 5—5 of Figure 4;

Figure 6 is a partial side elevation, in section on 6—6 of Figure 1;

Figure 7 is a sectional view on 7—7 of Figure 1; Figure 8 is a sectional view on 8—8 of Figure 1; Figure 9 is a sectional view on 9—9 of Figure 1; Figure 10 is a sectional view on 10—10 of Figure 2;

Figure 11 is a partial side elevation similar to Figure 6 but showing a replacement forepart mounted in the forward clamps;

Figure 12 is a fragmentary top plan showing a modified form of forward last-clamping means;

Figure 13 is a side elevation, on a smaller scale, of the rear portion of the saw table and base of Figure 1 showing the adjustable stop for setting the limit of a saw cut;

Figure 14 is a top plan of a modified form of device by which the method of the invention may be practiced;

Figure 15 is a top plan of a last with its forepart severed by a single, curved cross-cut, which may be accomplished with the device of Figure 14; and

Figure 16 is a top plan of a rear part of a last holder similar to that of Figures 1 and 2, but having means facilitating repeat positionings of corresponding portions of different lasts thereon.

The great utility of this invention, for that part of the shoe making industry which uses lasts, is based on recognition that in the remodeling of lasts the changes which are introduced by the remodeling occur, with rare exceptions, at regions which are forward of the hinge of the last. Or, if there be no hinge, they are forward of the location where the hinge would be if there were a hinge. The method of the invention provides for severing the forepart from an old last at a place a little back of the rearmost region where the changes from the old are to be introduced; and provides for the substitution, on the residue of old last left by such a removal of forepart, of a new forepart which will have been pre-modeled so as to embody all of the desired changes.

The severing of the forepart from the old last may be accomplished in various ways, as, with a band saw or circular saw, or by any other suitable cutter. And the severing may be by a single straight cross-cut; a plurality of straight cuts extending in angular relation; a single curved cut; or a combination of straight and curved cuts. However, it is essential that the severance occur at a region whose contour will be precisely the same in the remodeled last as in the old last, and that complementary cut surfaces be provided on the residue of the old and on the pre-modeled new forepart, so that these surfaces may fit together nicely.

To attain these ends the invention uses customary methods for the rough-turning and shaving of a new forepart, starting with a rough block having only the length of the forepart with slight excess. The shaving leaves the block devoid of the toe-stub that carried the forward "center" on which the block was turned; and leaves it in the desired final shape; and practically in the desired final size, for the subsequent scouring and polishing takes off only about a quarter of a size, which does not affect its fit to the body part.

The invention provides for the determining of a proper length for the residue to be retained of the old last, and a proper length for the replacement forepart, in order that the remodeled last shall be of desired length; and provides for a quick and perfect fitting of these two together. This latter is done by sawing each, at a place

where it is identical with the other in shape; and where their joined lengths will make the proper new length, so as to constitute, by the saw cut, surfaces, respectively on the residue and on the new forepart, which are complementarily identical in shape and size, these two surfaces to be later butted together for firm joinder. The cutting and the fitting is preferably done with the work positioned in a cradle which is adjustable, first, to receive and to hold at least the rear and mid-body of the old last, or at least to register a position thereof, and preferably at the same time to hold the forepart of the old last during the sawing operation which severs that old forepart from the mid-body; second, to guide the positioning of the rear and mid-body of a model of the whole remodeled last; third, to be adjusted so as to register by aid of that model the proper position for the remodeled forepart when the rear and mid-body are in the position already registered for them; fourth, to pose in the position thus registered the new forepart which is to be added to the residue of the old last, and, preferably to hold the new in that position while the saw is trimming the rear of this new forepart on a surface complementary to the forward surface of the said residue. If desired, guide points may be marked, one on the residue of body, and one on the new forepart, while they are separate, at top edges of their surfaces which are to go together. The putting of the two guide points together when those surfaces are together will guide the setting of the forepart with correct swing with respect to the body part. This marking is optional, being sometimes useful but not really necessary in practice.

It will be understood that, in cases to which the invention applies, the master model for the remodeled last can be made from one of the old lasts in the manner customary by adding layers of material to it to build up a fullness, or shaving material from it, so as to convert it to the desired new shape, according to the art of a model maker. When a rough block is put into a lathe and a forepart is turned, with that remodeled shape as a guiding master model, the rear portion of the forepart, at and back of the place for its fitting to the body part, will have a zonary region identical in shape with the corresponding region of the master model, and therefore identical in shape with the corresponding region of each of the old lasts which are to be remodeled. The old last which is to be remodeled is therefore cut off in this region, and the severed forepart is discarded. This may be done by a band saw, or by a circular saw, with the last mounted on a movable work table. The new rough-turned-and-shaved forepart, while it is positioned as above indicated, is severed in its corresponding region, its excess length being cut off at a proper distance from the foretip (according as the new toe is to be longer or shorter); and the severed rear portion of the forepart is discarded. This cut may be made by the same saw making a surface or surfaces complementary to the surface or surfaces left on the old last. The identity of contour shapes at the regions where these cuts are made permits of the old body and the new forepart being put together with perfect and firm fit of their cut surfaces, and with practical identity of external contour.

The zonary region for effecting this union may for brevity be referred to as a "mid-region" of the last. It is aft of all forward regions where any contour is to be changed; and it is forward

of the rear and main body portion of the last, containing the hinge and principal metallic obstacles to the making of a saw cut. There will ordinarily be ample length of space here where the contour of the old last is not to be changed, and where, therefore, each one of the old lasts will be like all the others of the same style and contour; and any one of them can be chosen to be that one which will be altered by hand to become the pattern or model for the new.

These steps are accomplished by ascertaining and recording in a cradle a known position of the old last, and severing its forepart on a surface having a known relation to that position; and, if desired, recording on the residue a point showing its relation to the said position; setting the new forepart in its appropriate portion of that same position, this having previously, in an operation by itself, been prepared in the desired new shape, with a small excess length of mid-region of the last; cutting off the excess at its rear, to a surface occupying the same relation to that position as did the forward surface of the body, at which the last was severed; recording on the forepart, if desired, a point having a known relation to the said position; and putting the surfaces of severance together, of the residue body and the residue forepart, with their recording points indicating the proper relation of these residues to each other for reproducing in their assembly the relation which each separately held with respect to said known position of the whole last when it was set therein.

In practice these steps may be accomplished thus:

First, setting the old last into a holder or jig, having adjustable points for support and for positional touch of the old last, and holding the last therein on a saw table which moves relative to the saw for the forepart to be cut off, and if desired, recording the said guide point by a mark on it, showing its position relative to the jig. Second, setting the previously turned and shaved forepart into the same jig, the forward points of which for support and touch have been adjusted slightly for the oversize and for any change of size, or further change of swing or spring that may be desired or for any contour change which occurred at points of contact of the jig with the new forepart; and moving the forepart relative to the saw to remove its rear excess length and to provide the said surface or surfaces which will be complementary to what was left by the cutting of the old last. The thickness of the saw is taken into consideration in determining where the new forepart is to be cut. A record point may be marked on the forepart which is at the same location, relative to the jig, as the mark on the body residue of last. Third, setting the body residue of last back into the jig for the fitting together of the old body and the new forepart.

While they are thus fitting together they can be compared with the pattern, and then secured together, as by glue and pressure, and by sunken screws and dowel pins, so as to make a solid last in which, for all practical needs of a shoe factory, the forepart is as if it were integral with the body part. That body part may be of the hinged type or otherwise as may be desired.

The finishing of the forepart may then be completed as in the case of a solid last, by scouring, polishing, dipping, and by adding a toe-iron if desired. As the smoothing of the rough finish by the scouring reduces the forepart only

about a quarter of a size, it is clear that the perfecting of the smoothness of joinder of surfaces involves no violating of the original form at this region of identity, as the forepart there is already in practically its final form. When put together the shape of each at the cut fits the other precisely; and the pre-existing shape of the body part does not need to be violated in making a smooth joinder.

10 It results therefore that the remodeled last requires only the labor for making and affixing the new forepart, with no spoilage of the body portion, and with a great saving over previous methods.

15 In my said co-pending application, Serial No. 113,816, the apparatus shown is for cutting on a curved line, on a radius which may be predetermined. With the apparatus herein disclosed, one straight cut, or two straight cuts extending in angular relation, may effect the severance, and make the surfaces for joinder both on the old last and on the pre-modeled new forepart.

20 Referring to the drawings, in the particular apparatus here represented, a saw table 10 may be fixed in position, and a band saw 12 operates in vertical travel relative to the plane of the top of table 10, travelling down through a slot at a mid-location in the table.

25 A base 14 for the work holder is slidably mounted on the table, and has a slot 15 extending inward from its rear edge for accommodating saw 12. The base has, on its under face, a guide bar or tongue 16 engaging in a groove 18 in the top of table 10, for guiding the movements of base 14 longitudinally of the table. Although 30 the tongue 16 and groove 18 are represented as extending along only one side of the base and table, similar guide means may be provided along the other side if desired, or other guide means may be employed.

35 In the arrangement represented, guide 16 projects rearward a distance beyond base 14, although this is not necessary, and extends through a slot 20 in a boss 22 which is secured on the rear edge of the table. As a matter of safety limit, the boss 22 may serve as a stop for travel of base 14 on table 10, rearward past the saw 12, by direct engagement of base 14 against boss 22. But, as represented, a block or lug 24 secured on guide 16 adjacent to the rear edge of base 14, will engage the end of a screw 26 in boss 22, so that by means of screw 26 the rearward limit of travel of base 14 may be adjusted, which will predetermine the travel of the saw into the last on a cutting stroke hereinafter described.

40 A last holder is pivotally mounted at 36 on a cross slide 38, on base 14, permitting the swinging and sliding transfer of last 28 between the two sawing positions thereof shown respectively 45 in Figures 1 and 2. The holder is arranged for holding a last lying on its side. It comprises a rear support 30 and a forward support 32, connected together by the rod 34, whose ends are similarly threaded, both having right pitch threads, or both having left pitch threads. One end of rod 34 is screwed into the rear support 30, and the other end is screwed into forward support 32.

45 The forward support 32 has the said pivotal connection 36 to the underlying bar 38 which can slide transversely on the base 14, and itself supports a carriage 33 slidably mounted on section 32 for adjustment in directions toward and from the rear support, longitudinally of the last. For

finger adjustment of section 33 on the section 32, a screw 40 is fixed on section 33, projecting forward therefrom loosely through a pair of spaced apart lugs 42 on section 32; and a nut 44 is threaded on that screw between the lugs.

The forward support section 33 has a series of rests for engaging a forepart of last. As represented, the rests comprise a vertical bumper wall 35 for engaging the tip of a last or forepart, a pair of vertically aligned clamp elements 46, 46, spaced a little rearward from the bumper 35 and adjustable on a right and left thread screw 48; and a second pair of vertically aligned clamp elements 50, 50, spaced rearward from the first pair, similarly adjustable on a right and left thread screw 52.

The clamp elements 46, 46 preferably are adjustable toward and from each other vertically by screw 48, in a slide 47 which itself is mounted for vertical adjustment by screw 49. And clamp elements 50, 50 likewise may be adjusted vertically, by their screw 52, in a slide 51 which itself is vertically adjustable by screw 53. With this structure, each pair of clamp elements may be moved bodily to position the clamp relative to more or less swing of the last; after which each clamp may be tightened to bring its clamp elements 46, 46 or 50, 50 into engagement with opposite side edges of the last, which lie in the holder with the top of the last facing horizontally. If desired, a bearing button 55 may be centrally located between clamp elements 46, 46 for engaging the bottom of the last, as in Figure 5.

The clamp 46, 46 preferably is additionally adjustable for lasts having different spring of toe. For this, the clamp 46, 46 and its slide 47 may be mounted on a block 57 which may be adjusted toward and from the last position, about pivot 59, by screw 61 (Figure 5). These various clamps do not merely serve the function of holding the last during its severance and the forepart rigid during its trimming. They also are contact points for learning, from the master re-model, just how the new forepart should be positioned and aligned; for preserving a registration of that position until the new forepart is put in; and then for positioning and aligning that forepart until it has been trimmed, whether the actual holding of the forepart is done by the described clamps or is done by hand guided by the registered positions. Therefore, for accuracy of the aligning, and for firmness of the holding during the sawing, it is well that the longitudinal spacing between the side clamps be as great as is convenient.

Supplementing the clamps 46, 46 and 50, 50 and located between them, a cable loop clamp may engage around the forepart of the last to hold the last within the clamp elements 46, 46 and 50, 50, and against button 55. This loop clamp may comprise the cable 54 whose ends are secured to opposite ends of a short shaft 56, mounted in the slotted ears 58, 58 on support section 33. A sleeve 60 is loose on shaft 56 and has a pair of cams 61, 61 fixed thereon and mounted in position for camming engagement against the carriage 33 on support section 32. A removable handle 62 on the cam facilitates rotation of the cams on shaft 56 to tighten the cable loop by movement of shaft 56 outward from last 28. Preferably the effective length of the cable clamp may be adjusted by a screw 63 at one or both ends of shaft 56, in which screw one end of the cable 54 may be secured.

Transverse sliding bar 38, to which support section 32 is pivotally connected at 36, is slidable

5 in a transverse groove 64 in base 14, between adjustable stops 66, 68, one at each side of the base.

The rear support 30 rests on base 14 and has an adjustable rest 70 on which the under side of the rear portion of a last may engage. Also it has a vertically adjustable button 72 for engaging the bottom of the last. These are contact points which cooperate with similar adjustable contact points 70' and 72' located as much further forward on the rear support 30 as is practicable to register the position of the heel and body part of an old last which is to be remodeled. The master re-model, which has similar contour at heel and body, is later to be set against these contacts and so be aligned similarly, in order that from this master the proper position of the forepart of the re-modeled last can be ascertained and registered, to be followed by the holding of that forepart in that registered position during making on it of a rear surface that will be correct for joinder to the body part of the old last. Preferably the rear bumper wall 74 is hinged at 76 to swing backward, and is held in operative vertical position by a latch 78. This permits the removal of the residue of an old last, after its forepart has been severed, without danger of accidentally cutting the residue when the base is being moved forward away from the saw.

30 If desired the adjustable rest 70 may be adjustable transversely of support 30, by being carried on a slide 80 which is adjustable transversely.

The operating is as follows: Referring to Figures 1 and 2, and assuming last 28 to be an old last which is to be remodeled, before proceeding with any cutting, zonary region Z thereon must be determined forward of which all of the changes are to occur. And a new forepart will have been made ready, modeled so as to embody all of the desired changes from the old forepart. According to the method of the invention, the remodeling of a last includes the steps of modeling a new forepart, as a separate element, which will embody all of the desired changes from the old last. This may be accomplished according to well-known last-modeling methods, using a master last of the desired size and contour as a guide or pattern. The new pre-modeled forepart will have extent rearward from the toe far enough to provide a zonary region Z, Fig. 11, thereon whose contour is precisely the same as the contour of a corresponding region of the old last. The obsolete or unwanted forepart of the old last is severed from the old body by cutting across the last in the said zonary region which is precisely the same as a region of the new forepart; and the rear portion of the new forepart is trimmed away by cutting across it at its corresponding region. The cut surface or surfaces left on the old last, and on the new forepart, are complementary to each other, so that the new forepart and the residue of the old last can be put together and secured together, so as to have the desired contour of the complete remodeled last. A final scouring process, will finish the remodeled last without materially changing the contour and size thus made.

The setting of the old last or of the new forepart, for a said cutting or trimming, will take into account the slight loss of length incidental to a saw's cut. This needed addition of length may be predetermined and be provided for in the setting of the old last for its cutting; or it may be provided for in the setting of the new forepart for its trimming cut. But, having been provided on one, it will not be provided on the other.

Thus the method conserves the body and heel

of the old, and avoids the stock, labor and costs of making a fresh body and heel part like the old.

Having decided where the cutting is to be done, the old last 28 may be turned on its side and be mounted in the last holder while the base 14 is at a forward location on table 10, away from the saw. Rear bumper 74 being in latched operative position, the rear end of the last is thrust against it, with rest 70 providing under support, and button 72, at one side, engaging the bottom of the heel portion. Next, the forward support carriage 33 may be adjusted, by turning nut 44, until the front bumper 35 thereon engages the tip of the last, after which the clamps 46, 46 and 50, 50 are adjusted to engage opposite sides of the last. The forepart of the last will have been inserted in the loose loop cable clamp 54, which now may be drawn tight by turning cams 61, 61; and the last is ready for the cutting operation.

The forward end of the last is to be moved to the right (Figure 1) by sliding of support 32 on base 14, until stop 66 is engaged by bar 38; and rear support 30 is swung to the left (Figure 1) into engagement with an adjustable stop 82, which involves a turning of the last holder about its forward pivot 36. The last then is in the position of Figure 1, ready to be fed toward the saw by movement of base 14 along table 10. If rod 34 were a straight connection between the forward and rear supports, it would be in the path of the saw. Rod 34 is formed with a U-bend 34', in the bowl of which the saw may work when at the inner extremity of a straight cut into the last. The place of the prospective first saw cut is indicated by the dotted lines at 84 in Figure 1; and in Figure 2 this first cut is shown as actually made in the last by full lines at 85. Because rod 34 has both ends on the same axis and threaded alike, its U-bend or bowl 34' may be swung about the axis of the rod without affecting the relative positioning of the front and rear supports. Thus the U-bend in Figure 1 is on the left of the saw path, and so accommodates the saw in making the initial cut in the last. In Figure 2 it has been swung under the last through 180° from its position of Figure 1, and is on the right side of the saw path, and accommodates the saw in making the second cut along the dotted line 86. Thus, although the fore and body parts are and continue to be rigidly connected by a stiff longitudinal rod, the result is attained that a complete severance of forepart from body part is made by the saw. The saw slot 15 in base 14 may be wide enough as at 15' to permit complete rotation of the U-rod for changing the longitudinal position of the U, when aligned with the slot. A removable handle 88 may be provided on rod 34 for this purpose.

Figure 2 shows the position of the last preparatory to making the second cut at 86, for completing the severance. The forward support 32 has been slid to the left as far as stop 66 will permit, and the rear support has been swung to the right into engagement with adjustable stop 90. The U-bend 34' of rod 34 is open toward the saw as heretofore explained. Both from the position in Figure 1 and from that in Figure 2, for the saw cutting, the base 14 is to be bodily moved along table 10 until stopped by screw 26 engaging block 24.

After the forepart has been completely severed by the second cut, the rear bumper 74 may be unlatched to permit withdrawal of the residue of old last rearward in direction away from the saw. The severed forepart will continue to be 75

held on its support until released, after base 14 has been moved away from the saw.

The cutting of the pre-modeled forepart, to provide on it a surface fitting that made on the body of the old last by the described cutting, will be preceded by a proper adjustment of the forward clamps to accommodate the changed contour of the new as compared with the old. This may be accomplished by mounting in the last holder the complete master last which was used as a guide or pattern for modeling the new forepart. In this the heel and body parts are like those from which the forepart has been severed. The rear support 30 and its contact points remaining unchanged, the re-model can be set and aligned therein in precisely the position in which the last was while being severed. This will set the forepart of the re-model where the new forepart of last should be; and the forward contacts can be set against it to ascertain and to register that position. The forward bumper may require adjustment forward or back to engage the tip of the master re-model; and the clamps 46, 46 and 50, 50 will be newly adjusted to suit the swing and the spring of the new toe.

Having adjusted the forward clamps to contact the master last, for registering the position of its forepart, the screws 48, 52 may be backed a slight observed amount, if necessary, for removal of the master and for insertion of the new forepart which has been made like it. When these screw clamps have been restored to position against the new forepart, and the cable clamp 54 has been tightened, the new forepart will be aligned and securely held in proper position to have its back end trimmed by the same sawing operations as were used for severing the old forepart from the old last.

Sometimes it is desired to use a master for the re-modeling of near-by sizes, without having a separate master for each. The new forepart, in that case will have been made with known allowances from the master's dimensions, and suitable adjustments of the clamp or contact can be made to correspond, and so to receive and hold foreparts of other sizes, or of other stick lengths. The latter usually are distributed equally at toe and heel, and one method is to adjust the rear support for half on rod 34, and to make the other half of adjustment at the forward barrier 35. Or the rear barrier 74 may be mounted in a longitudinal slide on the rear holder 30, for making the adjustment at the rear. Similarly the needed predetermined adjustments of the rests 70, 70' and of the clamp pieces 46, 46 and 50, 50 may be accomplished. Also the forward rest 55 will be suitably adjusted for the desired toe spring.

If a particular setting of elements accommodates a right last, or a right forepart of last as indicated in Figures 6, 11, a corresponding setting of slides 47 and 51, to the other side of zero on their respective scales S and S' will accommodate a left last or forepart. In the drawings, particularly in Figure 6, it happens that slide 51 is set at zero, so that no adjustment of it would be required in setting for a left last or forepart, but slide 47 would be adjusted to the other side of zero an amount corresponding to its represented departure from zero.

Before proceeding with the trim-cutting of the new forepart, the forward support 32 is to be moved forward relative to the rear support 30 a distance sufficient to make up for the small loss of length incident to a saw cut. Assuming that

the saw 12 cuts a swath one sixteenth of an inch wide, the needed addition on the length of new forepart to compensate will be slightly more than that, because of the cuts being at acute angles to the axis of the last. A movement along the axis of the last, sufficient to close a gap thus made, would be equal to the width of saw cut multiplied by the secant of the angle by which the line of the saw cut departs from being perpendicular to the axis of the last. Without computation, it can be determined simply by measuring at the said angle across any saw cut of the intended width. The pitch of threads on rod 34 having been made to be what has thus been determined, compensation for the loss incident to the saw cuts can be made by lifting the forward support 32 from the base 14, giving it one complete rotation on rod 34, and then setting it back on base 14.

For the trimming of the new forepart, to make the surface for joinder to the old mid-body part, the last holder then may be moved on base 14 to its position of Figure 1, and the base may then be moved against the saw which, entering the slot, will trim with a straight cut of the forepart, comparable to the cut at 84 (Figure 1) in the old last, but with the thickness of saw cut restored. Then the base is to be withdrawn from the saw; the last holder moved on the base to its position of Figure 2; and the second cut is to be made, corresponding to that which was made at 86 (Figure 2) in the old last.

The surfaces thus cut on old and new portions will accurately be complementary to each other; so that a permanent joinder of the residue of the old last with the pre-modeled new forepart may be effected in any suitable way, to make these two pieces become in practical effect integral. The joint may, for example, be made permanent by an adhesive substance supplemented by one or more screws. After the securing, the completing of the remodeled last needs only a final scouring such as is well known in the last industry, and the affixing of such metal plates as are desired, if any.

An outworn or out-moded integral last has thus been remodeled into a last which is integral in effect, at a cost but little greater than the cost of making a new forepart.

While the mechanism disclosed in this present application would be useful to an ordinary workman in practicing the process, as also would that shown in my said co-pending application, some workers are so skilled in the use of the band saw that one who is also proficient in the handling of lasts may be able to practice the process without either of these mechanisms, and without any implement except the saw and, probably, an underlying charted scale by which to gauge accurately the position in which to hold with his hand successively the old last, the new model, and the new forepart if there are contact rests which can be adjusted for registering the key positions, and for aid in reproducing the desired alignment, and to supplement the human hand in holding the wood steady during the sawing. In Figure 16 there is portrayed a means for guiding the setting of lasts on a last holder, comprising marks 114 on the holder by which the position of a portion of last may be observed, for a like setting of a corresponding portion of another last of the same size and contour. The guiding marks 114 are portrayed on a rear support similar to that of Figures 1 and 2 but ob-

viously they may be on the forward support as well.

The surfaces of joinder are not necessarily to be made at an angle to each other, although this is preferred as affording an element of strength of joint; if the entire cut is to be made in one plane, only a single traverse of the saw is needed. Nor does the practice of the process require any particular variety of saw. A band saw is illustrated as being probably most convenient; but obviously a jig saw could be used, also a circular saw if it be given vertical travel past work held as shown in the drawings. If its travel is to be horizontal, and is to make cuts like those illustrated, the basal plane support of the work should be set at any angle up to 90° from the horizontal illustrated so that the height of saw cut above the horizontal base plane would traverse the straight line apex of the U-surfaces.

In the modified form of device of Figure 14, a last may be mounted on a work holder 92 which may be mounted on base 94, for swinging movement about a pivot 96. The pivotal connection may be through the medium of a slide 98 which may be adjusted on the base to move the pivot 96 toward or from the saw 100, for changing the radius of the arc of cutting. In this case the last may rest on its bottom on the holder and be held by forward adjustable clamps 102, 104 and rear adjustable clamps 106, 108. The work holder 92 has a deep groove 110 extending inward from one side edge, to permit swinging of the holder to bring the last against the saw for the cutting.

The last of Figure 15 has its forepart severed from its rear part by a single curved cut 112, which may be accomplished in the device of Figure 14. Its zonary region, corresponding to Z of Figs. 1 and 2, is indicated at Z'.

The invention has been described with the steps recited in their more logical order of first cutting the old last and then trimming the new forepart to fit; but this order is immaterial and it would be an equivalent method if the new forepart were first trimmed and the old last were later severed in the same alignment, with a forward surface complementary to that already made on the new forepart.

In the claim the term "integral" is used, for brevity and convenience, to indicate a last in which the mid-body and forepart are one piece in practical effect, by way of distinction from lasts of that type in which the forepart is detachable. Thus a last in which there is a hinged piece, or surface plates, or a permanently secured forepart may be integral within the sense in which integral is here used.

I claim as my invention:

A method for equipping, with a new fore part, an old wooden last,—whose heel, body and forepart are integral in effect, the region thereof immediately back of the part which is to be changed being a mid-zonary region,—comprising the providing of a model of the desired last, including the shapes and relations of the old heel, body and mid-zone, and the desired new fore part; supporting that model on end-centers; supporting on end-centers a block of stock for a new fore part; rotating that model and that block on those centers, and turning the block to produce a fore part and mid-zone having the shapes and mutual relations of the fore-part and mid-zone in the model; determining the contour of a certain position in space by setting the model therein; setting the old last with its heel, body

and mid-zone portions in their respective parts of that determined contour position, and holding it there; cutting off the fore part of the so-held old last, to make cleavage surface located in mid-zonary region and having known relation to the said determined contour position, and rejecting the cut-off fore part; removing the residue of old last from the determined position; setting the turned block with its fore part and mid-zone in the appropriate portions of the determined contour position, and holding it there; cutting through the mid-zonary region of the turned block to

make cleavage surface having the said known relation to the said determined contour position, and rejecting the cut-off rear part of the mid-zone; putting together the said cleavage surface of the residue of old last, comprising the heel, body and part of mid-zone of the old last and the said cleavage surface of the residue of the turned block, comprising the fore part and part of mid-zone of that turned block; and securing 5 10 said residues together in the mutual relation thus established.

JOHN D. OWEN.
